UNITED STATES PATENT OFFICE.

BENJAMIN DE ALCALÀ, OF NEW ORLEANS, LOUISIANA.

TELEGRAPH-KEY.

1,265,887.

Specification of Letters Patent.

Patented May 14, 1918.

Application filed March 6, 1917. Serial No. 152,785.

To all whom it may concern:

Be it known that I, BENJAMIN DE ALCALÀ, a citizen of the United States, residing at New Orleans, in the parish of Orleans and State of Louisiana, have invented certain new and useful Improvements in Telegraph-Keys, of which the following is a specification.

This invention relates to new and useful improvements in a telegraph key.

The object of the invention is to provide a telegraph key of the character described which will automatically complete the circuit, after being used so that there will be no liability of the key being left open, accidentally, or otherwise, and the main line, connected to the key, thus being incapable of use between points located on opposite sides of the key in question.

20 A further feature of the invention resides in the provision of an improvement of the character described which will be simple in construction, accurate and positive in operation and which may be easily applied to 25 the ordinary telegraph key now in common use.

With the above and other objects in view, the invention has particular relation to certain novel features of construction, arrangements of parts and use, an example of which is given in this specification and illustrated in the accompanying drawings wherein:—

Figure 1 is a plan view of the key.

Fig. 2 is a side elevation thereof.

35 Fig. 3 is a transverse sectional view taken on the line 3—3 of Fig. 2.

Fig. 4 is a plan view of the automatic switch.

Fig. 5 is a side elevation thereof.

40 Fig. 6 is an end view thereof.

Figs. 7 and 8 show, respectively plan and end views of a contact employed, and

45 Figs. 9 and 10 show, respectively side and edge views of a connection whereby the switch is secured to the key lever.

Referring now more particularly to the drawings wherein like numerals of reference designate similar parts in each of the figures, the numeral 1 refers to the key base and the numeral 2 refers to the key lever mounted on trunnions 3, 3. This lever is equipped with a hard rubber handle 4 upon one end and an adjusting screw 5 at the other. By means of this adjusting screw 55 the range of lever movements may be controlled. There is a platina contact point

6 on the under side of the lever approximately half way between the handle 4 and trunnions 3. When the lever is pressed down, this point touches a similar point 7 supported by the frame, but insulated from it. The frame is provided with two binding posts 8 and 9, the former of which is connected directly to said frame and the latter of which is insulated from it. Connected to the binding post 8 is the wire 10 which leads to the relay and is thence connected with the main line on one side of the key and on the other side of the key the main line 11 leads directly from the binding post 9. The bar 12 connects the binding post 9 with the contact point 7 and is insulated from the base. The points 6 and 7 are normally held apart by means of the tension spring 13 which is supported by the base 1 and presses upwardly against the lever 2 between the trunnions and the handle. Telegraphing is accomplished by making and breaking of the contact between the two platina points 6 and 7. When the points are in contact a complete circuit is formed through the main line and when the handle 4 is released, the circuit is broken.

When the key is not in use, the circuit 85 should always be closed so that the main line can be used for the transmission of messages between points on the opposite sides of the key in question. For the purpose of closing the circuit, keys now in common use 90 are equipped with a switch 14, shown in dotted lines in Fig. 1. This switch is pivoted to the base 1 and when the key is in use the switch is manually opened as shown in Fig. 1 but when the key is not in use, this 95 switch should be closed by moving it into contact with the tongue 15 which is connected to the contact point 7 but insulated from the base. The circuit through the main line is thus completed. In a great many 100 cases, however, the operator forgets to close the switch and when it is left open, messages cannot be transmitted over the main line from points on opposite sides of the key and it is the object of this invention to provide a switch which will take the place of the switch 14 and which will automatically close the circuit through the main line when the key is not in use. This attachment consists of the contact 16 which is substantially 110 U-shaped in form, as shown in Figs. 7 and 8, having its free ends turned outwardly to

form abundant contact surface. This contact is mounted on the base but insulated therefrom and has the central orifice 17 through which the contact point 7 projects. 5 Pivoted to the lever 2 is the switch 18, this pivotal connection being effected by means of the clamp 19 which is secured to said lever and to which the switch 18 is pivoted. The outer end of this switch 18 is formed 10 of hard rubber, is arcuate in form and partially embraces the handle 4, but is slightly below the level of said handle and the underside of said end is provided with a bumper 20 which limits the range of the movement thereof. The opposite end of said switch is formed into a metallic head 21 elevated above the level of the handle 4, of considerable weight and is bifurcated forming downwardly projecting fingers 22, 22, which 15 are alined above the contact 16 and which rest thereon when said switch is released, completing the circuit through the main wires. When the key is being operated the lever is alternately pressed down by the pressure of the fingers of the operator upon the handle 4, bringing the points 6 and 7 20 into contact, and elevated by the pressure of the tension spring 13 bringing said point out of contact in the well known manner. 25 During this operation one finger of the operator rests upon the adjacent end of the switch 18 depressing said end and holding the fingers 22 out of contact with the contact 16 so that the circuit may be made and broken through the main wires by the manipulation of the lever 2. When the operator stops work the fingers 22 drop down upon the opposing contact 16 and on account of the weight of the head 21 are held in contact therewith, thus completing the circuit 30 through the key.

It is obvious that by this form of switch the circuit will be automatically closed when the key is not in use and the switch 14 now 45 in common use may be dispensed with, this switch having been shown in Figs. 1 and 2 only for the purpose of illustrating its use in connection with switches now commonly used. It is obvious that should an object 50 accidentally fall on the key it will be held by the handle 4, out of contact with the outer end of the switch 18 and will not open said switch or if it falls on the switch 18, the elevated head 21 will sustain said 55 object and the switch will be thereby held the more securely closed.

What I claim is:

1. In a telegraph key the combination with a base, of a key lever pivoted thereon and 60 electrically connected to one wire of the line and provided with a contact point, a handle carried by said lever, a contact point carried by the base and electrically connected to the other wire of the line, said points being normally out of contact, a switch pivoted to

said lever having its outer end free and arranged below said handle and its inner end bifurcated and formed into a weight which is elevated above its outer end and whose gravity normally holds the fingers of 70 said switch in electrical connection with said last mentioned contact point.

2. In a telegraph key the combination with a base, of a pivoted key lever mounted thereon and electrically connected to one wire of the line and provided with a contact point, a handle carried by said lever, a contact point carried by said base and electrically connected with the other wire of the line, 75 said points being normally out of contact, a switch pivoted to said lever, one end of which is formed into a weight whose gravity normally holds it into electrical connection with the contact point carried by said base, the other end of said switch being free and arranged below the level of said handle but adjacent thereto so that said free end may be readily depressed during the manipulation of the lever to lift the opposite end of the switch out of connection with said 80 contact point.

3. A telegraph key including a base, a pivoted lever electrically connected to one wire of the line and having a contact point, an opposing U-shaped contact point electrically connected with the other wire of the line, a switch pivoted to the lever one end of which is bifurcated and formed into a weight whose gravity normally holds its 95 fingers in electrical connection with the free ends of said last mentioned contact point, the other end of said switch being free and so arranged as to be readily depressed during the manipulation of said lever to disconnect the switch from said contact point. 100

4. A telegraph key including a base, a lever pivoted thereon and electrically connected to one wire of the line and provided with a contact point, a contact point connected to the other wire of said line, a handle through which said lever is manipulated, a clamp secured to the handle and forming a bearing, a switch pivoted to the clamp one end of which is normally in electrical connection with said last mentioned contact point and the other end of which is arranged adjacent and partially surrounding the handle whereby said last mentioned end may be readily depressed during the manipulation of said handle and the opposite end disconnected from said contact point, and a bumper carried by the free end of the switch to limit the range of its movement. 110

5. In a telegraph key the combination with a base, of a key lever pivoted thereon and 115 electrically connected to one wire of the line and provided with a contact point, of a contact point carried by the base and electrically connected to the other wire of the line, said points being normally out of con- 120

tact, of a clamp detachably secured to said lever and forming a bearing, a switch pivoted to said bearing having its outer end free and its inner end bifurcated and formed into
5 a weight whose gravity normally holds the fingers of said switch in electrical contact with the last mentioned contact point.

In testimony whereof I have signed my name to this specification in the presence of two subscribing witnesses.

BENJAMIN DE ALCALÀ.
